E. L. JOHNSON

FLASH LIGHT APPARATUS

Filed Dec. 23, 1925

Patented Jan. 25, 1927.

1,615,455

UNITED STATES PATENT OFFICE.

EVERARD L. JOHNSON, OF PATCHOGUE, NEW YORK.

FLASH-LIGHT APPARATUS.

Application filed December 23, 1925. Serial No. 77,259.

This invention relates to flashlight apparatus or guns adapted for use by professional or amateur photographers in studios, homes and other places, and the object of the invention is to provide a gun or apparatus of the class specified which by reason of its construction will be rendered fool-proof in operation, means being employed to prevent the accidental ignition of the explosive powder by the sparking or igniting means employed until the gun or apparatus has been placed in its operative position, particularly within a flash-bag employed for this purpose; a further object being to provide improved means for controlling and regulating the operation of the spark generating device; a further object being to provide improved means for controlling and operating a door member which when in operative position prevents the back flash of powder into the mechanisms or apparatus of a gun; and with these and other objects in view the invention consists in an apparatus of the class and for the purpose specified which is simple in construction, efficient in use, and which is constructed as herein-after described and claimed.

The invention is fully disclosed in the following specification, of which the accompanying drawing forms a part, in which the separate parts of my improvement are designated by suitable reference characters in each of the views, and in which:-

Fig. 1 is a sectional view of a part of a cabinet and door construction controlling admission to said cabinet and showing my improved flash gun mounted in connection therewith and indicating the method of its use;

Fig. 2 is an inside view of the cabinet showing the gun in operative position;

Fig. 3 is a transverse sectional view on the line 3—3 of Fig. 2;

Fig. 4 is a section on the line 4—4 of Fig. 3; and,

Fig. 5 is a face view of the gun with the cover thereof removed and with part of the construction broken away and in section.

The invention shown and described is an improvement on flashlight apparatus, such as shown and described in prior patents granted to me, November 7, 1922, No. 1,434,438 and April 3, 1923, No. 1,450,502, the former patent showing the flash gun proper while the latter shows a flash-bag and improved door construction.

In the accompanying drawing I have shown at 10 my improved flash gun, which is mounted in connection with and movable with the outer door 11 of a flash-bag or other support 12, having a door opening 13 closed by the door 11 and also by a spring hinge door 14 which is movable within the receptacle of the flash-bag 12, the movement being imparted to the door 14 by a hook-shaped arm 15 on a supporting bracket 16 secured to the door 11 and on which bracket the gun 10 is mounted and held in position by a set screw 17. When the door 14 is composed of wood a metal plate 14^a is mounted on the face of the door in connection with which the arm 15 operates, and the spring hinge 14^b for the door 14 normally operating to hold the same in closed position as shown in dot and dash lines in Fig. 1 of 75 the drawing. The outer door 11 is held in its closed position by a clip 18, and when this clip is removed the tension of the spring hinge of the door 14 will operate to close said door and move the door 11 as well as 80 the gun 10, which is supported thereby, outwardly through the opening 13 of the cabinet 12 as indicated in dot and dash lines in Fig. 1 of the drawing.

My improved gun, in the construction 85 shown, comprises a box-shaped casing 19, the open side face of which is closed by a cover 20 held in place by a winged nut 21 threaded upon a bearing pin 22 mounted in the casing, and alining pins or dowels 23 on the casing pass into the cover and serve to hold the same in proper position. The bottom of the casing adjacent the back wall thereof is provided with an extended flange 24 with which a trough 25 is detachably connected, and the casing is provided adjacent one corner portion thereof with a chamber 26 opening outwardly into the trough 25 and into the casing, as seen at 27 in Fig. 5 of the drawing.

Rotatably mounted upon the pin 22 is a spark generating device 28 having a semi-circular face on which is mounted a segment 29, having a roughened or filed surface for engagement with a piece of flint mounted in a support 30 in the casing, and an adjustment screw 31 being employed for regulating the tension of the flint upon the roughened surface of the segment 29. The member 28 is provided with a radial arm 32 with which is connected a coil spring 33 and an adjustment screw 34 mounted in the

casing and coupled with said spring to control and regulate the tension thereof, said screw being adjusted on a nut 35 externally of the casing 19.

5 The flint supporting member 30 is arranged adjacent to the point 27 where the chamber 26 opens into the casing, and the segment 29 on the member 28 is also arranged adjacent to said point, whereby in the 10 operation of the member 28 sparks will be directed into the chamber 26 and thus into the trough 25 to ignite the flash powder placed therein, and a door 36 is pivotally mounted within the casing and operated in 15 one direction by a spring 37, and the spring holds the door normally in a closed position, as seen in Fig. 5, and a cam face 38 on the member 28 operates to move the door 36 into inoperative position and to hold the same in 20 such position as seen in Fig. 4 of the drawing. The rubber or other cushion or buffer 39 is mounted in the casing 19 and in connection with which the member 28 operates to prevent any noise or sound when said 25 member is released and operated by the spring 33 as later described.

I also employ a pawl 40 which is pivotally mounted within the casing provided with a projecting nose 41 adapted to engage a 30 notch 42 in the segment 29 to hold the member 28 in position under the tension of the spring 33, it being understood that the member 28 is set in such position by hand by the operator pushing upon a finger-piece 43 at 35 the end of the arm 32, which finger-piece extends through the cover 20 of the casing and operates in an elongated arc-shaped aperture 44 therein, note Fig. 4 of the drawing. A coil spring 45 is connected with the pawl 40, 40 said spring having an adjustment screw 46 to regulate its tension, the screw being adjusted by a nut 47, said spring serving to hold the pawl in operative position, the pawl is released by a plunger 48 adapted to strike the free end of the pawl 40, said plunger 45 being actuated by an air bulb 49 placed in communication with the plunger through a flexible tube 50, note Fig. 5 of the drawing. The tubing 50 in the use of the device as 50 illustrated in Figs. 1 and 2 is adapted to pass through an aperture 51 in the door 11 in order that the bulb 49 may be external of the cabinet 12 as will be apparent.

Pivotally mounted in connection with the 55 cover 20 at 52 is a safety control lever 53, the inner end portion 54 of which is adapted to normally lie in the path of the finger-piece 43 to prevent the release of the spark generating member 28 even though the pawl 40 might be moved into inoperative position 60 by the compression of the bulb 49 or by any other means, and the outer end portion 55 of the lever is provided with a beveled face adapted to operate in connection with a pin 65 56 on the door 14 to move the lever 53 or

the inner end portion 54 thereof into inoperative position as shown in full lines in Fig. 2 of the drawing when the door 11 is closed as shown in full lines in Figs. 1 and 2; it being understood that the relative 70 pivots of the door 11 of the flash-bag 12 are such that the lever 53 will not engage the pin 56 until the door 11 is in a closed or practically closed position, and a spring 57 is secured to the cover 20 and to the end 55 of 75 the lever to normally hold the end 54 thereof in operative position. It will also be understood that when the bulb 49 is operated to set off the gun and assuming that the gun 10 is in the flash-bag 12 as shown in Figs. 1 and 2 of the drawing, the operation of said bulb will move the plunger 48 in position to strike the pawl 40 releasing the member 28 which moves from the position shown in Fig. 4 into a position substantially 80 similar to that shown in Fig. 3, and the sparks generated by the engagement of the segment 29 with the flint in the holder 30 are directed into the chamber 26, after which the door 36 closes the communication between the chamber 26 and the interior of the casing.

It will be understood that while I have shown certain details of construction for carrying my invention into effect, that I 85 am not necessarily limited to these details, and changes in and modifications of the structure herein shown and described may be made, within the scope of the appended claims, without departing from the spirit of my invention or sacrificing its advantages.

Having fully described my invention, what I claim as new and desire to secure by Letters Patent, is:—

1. A flashlight gun comprising spark generating elements, one of said elements being movable with respect to the other in the generation of sparks, means for normally holding said movable element in predetermined position, a spring for actuating the movable element when released, and automatically actuated means for preventing the operation of the movable element until the gun is in predetermined position and ready for use. 105

2. A flashlight gun comprising spark generating elements, one of said elements being movable with respect to the other in the generation of sparks, means for normally holding said movable element in predetermined position, a spring for actuating the movable element when released, automatically actuated means for preventing the operation of the movable element until the gun is in predetermined position and ready 110 for use, and the tensional means of said movable element being adjustable. 125

3. A flashlight gun of the class described comprising a casing, spark generating elements mounted within said casing, said cas- 130

ing having an external powder receiving receptacle, means for placing said sparking elements in communication with said receptacle, and automatically actuated means co-operating with one of said sparking elements for retaining the same against operation until the gun is in proper position for use.

4. A device of the class described comprising a casing having an external powder receiving receptacle in communication with the interior of the casing, means within the casing for generating sparks which are adapted to pass through said communication to said receptacle, and automatically actuated means for rendering the spark generating means inoperative until the device is in position for use.

5. A device of the class described comprising a casing having an external powder receiving receptacle in communication with the interior of the casing, a tensionally operated rotatable sparking element in said casing co-operating with flint supported in the casing to generate sparks adapted to be directed through the communication into said receptacle, a pawl for normally holding said element in operative position, manually operated means for releasing said pawl to permit of the operation of said element, and automatically actuated means co-operating with said element to prevent the operation thereof until the apparatus is in proper position for use.

6. A device of the class described comprising a casing having an external powder receiving receptacle in communication with the interior of the casing, a tensionally operated rotatable sparking element in said casing co-operating with flint supported in the casing to generate sparks adapted to be directed through the communication into said receptacle, a pawl for normally holding said element in operative position, manually operated means for releasing said pawl to permit of the operation of said element, automatically actuated means co-operating with said element to prevent the operation thereof until the apparatus is in proper position for use, and means for adjusting the tension of the operating means for said element.

7. A device of the class described comprising a casing having an external powder receiving receptacle in communication with the interior of the casing, a tensionally operated rotatable sparking element in said casing co-operating with flint supported in the casing to generate sparks adapted to be directed through the communication into said receptacle, a pawl for normally holding said element in operative position, manually operated means for releasing said pawl to permit of the operation of said element, automatically actuated means co-operating

with said element to prevent the operation thereof until the apparatus is in proper position for use, means for adjusting the tension of the operating means for said element, a door controlling the communication between the casing and said receptacle, said door being normally held in open position by said element, and tensional means for moving the door in a closed position.

8. An apparatus of the class described comprising a flash cabinet having an opening therein, a dual door construction controlling said opening, a flashlight gun supported in connection with and movable with one of said doors and adapted to be extended through the cabinet and to be moved thereinto, said gun comprising a casing having an external powder receiving receptacle, means within the casing for generating sparks to ignite the powder placed in said receptacle, and a safety device co-operating with the spark generating means to prevent the operation thereof until the gun is contained within the flash-bag.

9. An apparatus of the class described comprising a flash cabinet having an opening therein, a dual door construction controlling said opening, a flashlight gun supported in connection with and movable with one of said doors and adapted to be extended through the cabinet and to be moved thereinto, said gun comprising a casing having an external powder receiving receptacle, means within the casing for generating sparks to ignite the powder placed in said receptacle, a safety device co-operating with the spark generating means to prevent the operation thereof until the gun is contained within the flash-bag, and means co-operating with said safety device to move the same into inoperative position when the gun is within the flash-bag.

10. An apparatus of the class described comprising a flash cabinet having an opening therein, a dual door construction controlling said opening, a flashlight gun supported in connection with and movable with one of said doors and adapted to be extended through the cabinet and to be moved thereinto, said gun comprising a casing having an external powder receiving receptacle, means within the casing for generating sparks to ignite the powder placed in said receptacle, a safety device co-operating with the spark generating means to prevent the operation thereof until the gun is contained within the flash-bag, means co-operating with said safety device to move the same into inoperative position when the gun is within the flash-bag, and manually operated means extending through the flash-bag when the gun is contained therein for manually actuating spark generating means employed.

11. An apparatus of the class described comprising a frame having a door opening

- therein, two doors controlling said opening, a flashlight gun mounted in connection with one of said doors and movable therein whereby said gun may be extended through 5 said door opening in both directions, means whereby the operation of one door will cause the other door to be operated, said flashlight gun comprising a casing having an external powder receiving receptacle, spark generating means within said casing, and a safety device co-operating with said spark generating means whereby the same may be operated in one position only of said flashlight gun.
12. An apparatus of the class described comprising a frame having a door opening therein, two doors controlling said opening, a flashlight gun mounted in connection with

one of said doors and movable therein whereby said gun may be extended through 20 said door opening in both directions, means whereby the operation of one door will cause the other door to be operated, said flashlight gun comprising a casing having an external powder receiving receptacle, 25 spark generating means within said casing, a safety device co-operating with said spark generating means whereby the same may be operated in one position only of said flashlight gun, and means on one of said door members for moving said safety device into inoperative position.

In testimony that I claim the foregoing as my invention I have signed my name this 11th day of Dec. 1925.

EVERARD L. JOHNSON.
